UNITED STATES PATENT OFFICE.

ALFRED HOPKINS, OF BOSTON, MASSACHUSETTS, ASSIGNOR, BY MESNE ASSIGNMENTS, TO HOPKINS-TULL MACHINERY CO., OF PHILADELPHIA, PENNSYLVANIA, A CORPORATION OF PENNSYLVANIA.

STRETCHER.

Application filed April 16, 1927. Serial No. 184,373.

This invention relates to an adjustable portable stretcher on which lace and other curtains, and divers other articles, such as blankets, may be stretched after washing, 5 while being dried.

The invention relates to the type of stretcher disclosed in Letters Patent of the United States, No. 1,828,995, granted to me.

The principal object of the present invention 10 is to improve stretchers of the indicated character, to the end that greater facility will be had in arranging articles on the stretcher in a stretched condition, and which will be particularly adapted for supporting blankets, 15 draperies and the like in a stretched condition.

The nature of the invention and its distinguishing features and advantages will appear when the following specification is read in conjunction with the accompanying drawings, in which—

Figure 1 is a side view of a stretcher embodying the invention.

Fig. 2 is a view looking at one end of the stretcher.

Fig. 3 is a view looking at the opposite end 25 of the stretcher.

Figs. 4, 5 and 6 are detail sectional views, respectively taken on the lines 4—4, 5—5, and 6—6 of Fig. 1.

Fig. 7 illustrates one of the features of the 30 frame.

The improved stretcher of the present invention includes a frame composed of a pair of horizontal top members 10, a pair of horizontal bottom members 11, and end members 12 and 13, which connect the members 10 and 11 together to form a rigid oblong rectangular frame. A pair of horizontal track members 14 are connected between the end members 12 35 and 13. The top members 10, and end members 12, each have material engaging means such as strips of card clothing 15, the pins of which are adapted to impale the articles to be stretched. The frame is provided with horizontal pairs of members 16 each of which carries card clothing 17. The members 10, 14 and 16 are arranged in parallelism in superposed relationship. Means is provided in conjunction with each pair of members 16 to 45 support them from the end members 12 and 13 in different adjusted positions. The said means includes a bolt 18 slidable in a guide 19 secured to the members 16. A spring 20 which surrounds the bolt 18, has one end in

contact with the guide and the opposite end 55 in contact with a collar 21 on the bolt 18. The end 22 of the bolt is adapted to enter either of the holes 23 in the end member 13. The spring 20 functions to project the end 22 into either one of the holes 23. A lever 24 is connected with the bolt 18 to retract the end 22 from the holes. The lever 24 is operable in conjunction with a handle 25. The lever 24 is connected with a bolt 26 slidable in a guide 27 secured to the members 16. A spring 28 60 which surrounds the bolt 26, has one end in contact with the guide 27, and the opposite end in contact with a collar 29 on the bolt 26. One end of the bolt 26 is adapted to enter either one of a series of holes which will occur 65 in the end member 12. The spring 28 functions to project the end of the bolt 26 into either of said holes. The lever 24 is connected with the bolt 26 by a wire 30 so that both bolts 18 and 26 will be retracted at the same time 70 by manipulating the lever 24.

In order to counter balance the pairs of members 16 there are provided weights 31. One weight 31 is connected with the opposite ends of one pair of members 16 by chains or 75 the like 32, which pass over pulleys 33 on parts of the frame. The other weight 31 is connected with the opposite ends of the other pair of members 16 by chains or the like 34, which pass over pulleys 35 on parts of the 80 frame. The weights 31 move respectively in tubular members 36 connected together at the ends by bracket members 37, attached to the end member 13. The pairs of members 16 co-operate with the pair of top members 10 to 85 support lace curtains and closely kindred articles in a stretched condition while being dried.

A pair of connected vertical members 38 are provided. The members 38 at opposite ends 90 respectively have small arms 39. Each arm 39 has a pin 40. The pin 40 on the upper arm 39 moves between the top members 10 and the pin 40 on the lower arm 39 moves between the bottom members 11. The pins 40 serve to 95 guide the members 38. Each of the members 38 has a strip of card clothing 41. A bracket 42 is attached to the members 38. The bracket 42 carries pairs of wheels 43 which travel 100 on the track members 14. A clamping device 44 serves to hold the members 38 in different 105 positions of adjustment.

In stretching a blanket or closely kindred

article use is made of rollers 45. These rollers are journalled in suitable fixed bearings 46 respectively on parts of the frame and disposed outermost with respect to the parts of the frame which carry the rollers. Any preferred number of rollers 45 may be used. They may be disposed in pairs as shown at the top and at one end of the frame. A blanket or the like 47, Fig. 6, is passed over the rollers 45 and the ends of the blanket may be engaged by the card clothing or lower pair of members 16; according to the size of the blanket. The members 16 will be moved downwardly stretching the blanket and the bolt 26 will be projected into one of the holes 23 to hold the members 16 in position against movement, thus maintaining the blanket in a stretched condition. In this manner the blanket will be held in a stretched condition while drying. It will also be obvious that the rollers 45 at the end of the frame may be utilized in conjunction with the members 38 and the card clothing 41 carried thereby for holding an article in a stretched condition while drying.

To stretch a comparatively small curtain or blanket, one edge is fastened to card clothing 15 on one of the members 10, and the other edge is fastened to card clothing 17 on one of the lower members 16. A standard or smaller sized curtain will have one edge fastened to card clothing 17 on one of the adjustable upper members 16, and the other edge will be fastened to the card clothing 17 to one of the lower adjustable members 16. The reason for providing the upper adjustable members 16 is so that they can be located at a more convenient height. An operator can stand on the floor and fasten the top edge of a blanket or curtain to one of the upper members 16 instead of being compelled to use one of the top members 10, when the width of a curtain

or a blanket is small enough to be stretched between an upper member 16 and a lower member 16.

The frame and parts mentioned connected therewith may be suspended from a fixed track or rail 50 by means of hangers 51 connected with the top member 10. The said hangers 51 have rollers 52 which travel along the track or rail 50. The said track or rail 50 may be extended into a drying room, the track or rail 50 being long enough to support the frame outside of the drying room while the articles are being applied before being moved into the drying room.

I claim:

1. In a stretcher, a rectangular frame, a pair of rollers mounted on the top members of this frame in spaced relation thereto and to each other, and over which the article to be stretched is passed with its ends depending therefrom, and a pair of spaced horizontal members adjustably mounted in the frame, each member of the pair having means for securing the depending ends of the article thereto.

2. A stretcher comprising a rectangular frame having two of its members provided with means for securing an article thereto, horizontal members slidably and adjustably mounted in the frame and each provided with means for securing said article thereto, means for counter-balancing said last members, said last means including cables secured to the members and having weights at their ends and tubular guides on the frame and in which the weights work; and a vertical member adjustably mounted in the frame and having means for securing said article thereto, said members being cooperative to stretch said articles.

ALFRED HOPKINS.
